INVENTOR

UNITED STATES PATENT OFFICE

100,388

DESIGN FOR A GLOVE

Louis Postman, New Rochelle, N. Y.

Application August 9, 1935, Serial No. 58,037

Term of patent 3½ years

To all whom it may concern:

Be it known that I, Louis Postman, a citizen of the United States of America, residing in New Rochelle, county of Westchester, and State of New York, have invented a new, original, and ornamental Design for a Glove, of which the following is a specification, reference being had to the accompanying drawing, forming part thereof, wherein,

Figure 1 is a front view of a glove showing my new design.

Figure 2 is a rear view of the glove shown in Figure 1.

The irregular lines at the top of the glove, as shown in Figure 2, represent a gathering of the material, due to the presence of elastic, in the inner part of the glove.

The dominating features of this design reside in the provision of double rows of shirring and in the provision of a wing-shaped strap.

I claim:

The ornamental design for a glove, substantially as shown, and described.

LOUIS POSTMAN.
